SLIDER FOR SLIDE FASTENERS

Delbert B. Gilmore, Erie, Pa., assignor to Hookless
Fastener Company, Meadville, Pa., a corpora-
tion of Pennsylvania

Application November 12, 1934, Serial No. 752,579

4 Claims. (Cl. 24—205)

This invention relates to sliders for slide fasteners and particularly to a locking type slider.

Various forms of locking devices have been proposed for retaining the slider in the desired position on the rows of fastener elements in a slide fastener. More recently automatic lock sliders have been introduced which comprise generally a locking member movable relative to the slider and normally held in locked position by a spring or its equivalent, such member being automatically moved to unlocked position when the pull tab is lifted to operate the slider.

The object of my invention is to provide an improved form of automatic lock slider for slide fasteners which shall be neat in appearance, simple in construction and which shall possess the necessary ruggedness and strength to withstand the severe strains imposed upon such devices in actual use.

In the accompanying drawing I have shown for purposes of illustration one embodiment which my invention may assume in practice. In the drawing:

Fig. 1 is a front view of a portion of a slide fastener and slider equipped with my improved automatic lock;

Fig. 2 is a central longitudinal cross-section;

Fig. 3 is a cross-section on line 3—3 of Fig. 1; and

Fig. 4 is a perspective view of the locking member detached.

I have shown a conventional slide fastener having flexible tape stringers 5, 6, with rows of interlocking elements 7, secured to their meeting edges. The slider used for engaging and disengaging the fastener elements may be of a well-known form comprising a body member 8, having an interior channel 9, of the desired shape, for guiding the fastener elements into and out of engagement.

In the upper or front wall of the slider there is an opening 10 shown herein, of rectangular cross-section, but which may be of any suitable shape. A locking member 11 is loosely fitted in the opening 10, so as to be free to move in said opening into and out of locking position. The locking member carries on its interior face locking projections 12 and 13 which are staggered relative to one another so as to engage in spaces between the rows of fastener elements. Such spaces are, of course, staggered relative to one another as seen in Fig. 1. The locking projections have inclined surfaces on one side and perpendicular surfaces on the other side, so that the locking member will never obstruct a deliberate closing

movement of the slider, but rather cam up over the fastener elements.

A slider of a conventional type is employed, having a lug 14 extending longitudinally throughout substantially the entire length of the slider. Such lug is hollowed or recessed out at 15 to form a loop 16, which passes centrally over the locking member. The locking member has upwardly extending guide arms 17, 18, which engage on opposite sides of the loop and effectively guide the upper end of the locking member in its movement. A resilient device, herein in the form of a coiled spring 19, is placed between the loop and locking member so as to press the locking member normally toward locking position. Preferably the spring is arranged between the arms 17, 18 which prevent it from accidental displacement. The pull tab 20 has trunnions 21 engaging in elongated recesses 22, in the locking member. Thus when the pull tab is lifted to operate the slider in either direction, the locking member will be lifted against the compression of the spring 19, and disengage the locking projections 12, 13 from the fastener members, so that the slider can be freely moved in either direction.

In assembling the parts of the slider, the coil spring and locking member can be placed in the opening 10 before the slider is placed on the fastener elements. The trunnions of the pull tab will serve to hold the locking member from dropping out of the opening 10, until the slider is assembled on the fastener.

As a result of my invention it will be observed that an improved automatic lock slider has been provided which utilizes a conventional form of slider and which is not likely to get out of order because of its rugged and durable construction.

While I have shown and described in this application one embodiment which my invention may assume in practice, it will be understood that this description is merely for the purposes of illustration and that various other forms may be devised within the scope of my invention as defined in the appended claims.

What I claim as my invention is:

1. A slider for slide fasteners comprising a body member having an interior channel, the body member having also an opening communicating with said channel, a slider locking member movably mounted in said opening and having locking projections adapted to engage between fastener elements in the slider channel, means for retaining said locking member in position comprising a loop attached to the slider body and extending centrally over said locking member, a

spring between said loop and said locking member which normally presses said locking member inwardly toward locking position, and an operating member attached to said locking member.

- 5 2. A slider for slide fasteners comprising a body member having an interior channel, the body member having also an opening communicating with said channel, a slider locking member movably mounted in said opening and having locking 10 projections adapted to engage between fastener elements in the slider channel, said locking member having upwardly extending spaced-apart arms, a relatively stationary guide element secured to the slider and positioned between said arms, 15 and a lock operating member attached to said upwardly extending arms.

3. A slider for slide fasteners comprising a body member having an interior channel, the body member having also an opening communicating with said channel, a slider locking member movably mounted in said opening and having locking 20 projections adapted to engage between fastener elements in the slider channel, a longitudinally extending loop on said slider passing centrally over said locking member, and means carried by 25

said locking member and cooperating with said loop to guide the same, and a spring positioned between said loop and locking member for normally pressing the locking member toward locking position, and a slider pull member attached to said locking member.

4. A slider for slide fasteners comprising a body member having an interior channel, the body member having also an opening communicating with said channel, a slider locking member movably mounted in said opening and having locking 10 projections adapted to engage between fastener elements in the slider channel, said locking member having upwardly extending guide arms, a longitudinally extending lug on said slider 15 hollowed out to form a loop in the central portion which passes over said locking member, a spring positioned between said loop and said locking member for normally pressing the locking member toward locking position, the pair of arms 20 on said locking member arranged on opposite sides of said lug for guiding said locking member, and a slider operating member secured to said locking member.
